US00D440192S

(12) United States Design Patent **(10) Patent No.:** **US D440,192 S**
Sauter **(45) Date of Patent:** **** Apr. 10, 2001**

---

(54) IDENTIFICATION APPLIQUE

(75) Inventor: **Ulrich Sauter, Tiefenbronn (DE)**

(73) Assignee: **Dr. Ing. h.c.F. Porsche
Aktiengesellschaft, Stuttgart (DE)**

(**) Term: **14 Years**

(21) Appl. No.: **29/115,327**

(22) Filed: **Dec. 13, 1999**

(30) Foreign Application Priority Data

Jun. 12, 1999 (DE) 4 99 05 597

(51) LOC (7) Cl. **12-16**

(52) U.S. Cl. **D12/190**

(58) Field of Search D12/190, 400,
D12/197; 428/913.3, 914; 296/196-197,
209; 293/128; D20/11; 280/163, 164.1,
169, 848, 768, 762, 153.5
